UNITED STATES PATENT OFFICE

163,140

COMBINATION MIRROR AND LIPSTICK CASE

Irving Roth, Jackson Heights, N. Y., and
Maxwell F. Bower, Riverside, Conn.

Application July 26, 1950, Serial No. 11,422

Term of patent 3½ years

(Cl. D86—10)

To all whom it may concern:

Be it known that we, Irving Roth and Maxwell F. Bower, both citizens of the United States, residing at No. 34—20 74th Street, Jackson Heights, county of Queens, and State of New York, and at Maple Road, R. D. No. 1, Riverside, county of Fairfield, and State of Connecticut, respectively, have invented a new, original, and ornamental Design for a Combination Mirror and Lipstick Case, of which the following is a specification, reference being had to the accompanying drawing, forming part hereof.

In the drawing:

Fig. 1 is a front view of the combination mirror and lipstick case embodying the design;

Fig. 2 is a side view thereof;

Fig. 3 is a top plan view thereof; and

Fig. 4 is a rear view thereof.

We claim:

The ornamental design for a combination mirror and lipstick case, substantially as shown.

IRVING ROTH.

MAXWELL F. BOWER.
